DESIGN FOR A PERFUME DISPLAY STAND

Adolph H. Cohn, New York, N. Y.

Application January 18, 1939, Serial No. 82,416

Term of patent 3½ years

To all whom it may concern:

Be it known that I, Adolph H. Cohn, a citizen of the United States of America, residing in New York city, in the Borough of Manhattan, county and State of New York, have invented a new, original, and ornamental Design for a Perfume Display Stand, of which the following is a specification, reference being had to the accompanying drawing, forming part thereof, wherein

I claim:

The ornamental design for a perfume display stand, substantially as shown.

ADOLPH H. COHN.
